UNITED STATES PATENT OFFICE.

CHRISTIAN KORTE, OF LEEDS, ENGLAND, ASSIGNOR OF TWO-THIRDS TO CAMBELLS AND HUNTER LIMITED, OF LEEDS, ENGLAND.

BRIQUETING-MACHINE.

1,242,704.

Specification of Letters Patent.

Patented Oct. 9, 1917.

Application filed February 1, 1916. Serial No. 75,511.

To all whom it may concern:

Be it known that I, CHRISTIAN KORTE, a subject of the King of Great Britain, and resident of Leeds, in the county of York, England, have invented a certain new and useful Improvement in Briquetting-Machines, of which the following description, having reference to the accompanying sheets of drawings, is a specification.

10 My invention relates to the type or class of briquetting machines wherein mechanical devices are employed (for exerting the pressure upon the granulated substances that are to be formed into briquets) in conjunction with hydraulic mechanism for relieving the pressure and more especially to those machines which are designed to be employed in the production of briquets from metal borings and the like. In this class or type 15 of machine it is essential that provision should be made for applying equal pressure to the resultant briquet whether said briquet is a long one or a short one as is well known, and the object of my present invention is 20 the production of devices which when the desired pressure is imparted to the briquet being produced, the pressing tools are immediately relieved of the excessive pressure by the novel means I now employ, and yet 25 in such a manner as to avoid shocks and jerky vibrations irrespective of the length of the resultant briquet, while the same devices are arranged in conjunction with driving mechanism which will gradually decrease in speed as the maximum or desired 30 pressure is reached.

In the accompanying drawings:—

Figure 1 is a side elevation of a machine produced in accordance with my invention. 40 Fig. 2 is a front elevation of the parts shown by Fig. 1 as seen in the direction indicated by the arrow *a*.

Fig. 3 is a plan of the parts shown by Figs. 1 and 2.

Fig. 4 is a longitudinal sectional elevation of parts shown by Figs. 1 and 2.

Fig. 5 is a sectional plan of parts shown by Fig. 1.

Fig. 6 is a sectional elevation drawn to an enlarged scale of certain devices herein- 50 after described.

Fig. 7 is an elevation of the parts shown

by Fig. 6 as seen in the direction indicated by the arrow *b*.

Fig. 8 is a plan of parts shown by Fig. 6. 55

Figs. 9 and 10 are side elevation and plan respectively of driving mechanism herein- 60 after described.

Similar letters and figures of reference refer to similar parts throughout the several 65 views.

A indicates the base upon which the upper parts B forming the framework of the machine, are mounted.

In the upper part of the framework B 65 lateral openings 2 are formed on each side so that arms 3^a and 3^b of a cylinder 3 may take into them and be guided thereby as they are moved in a vertical path herein- 70 after described. Connected to these arms 70 or to ears extending therefrom are the connecting rods 4, 4^a, which extend downward to be actuated by the cranks 5 and 5^a formed on the crank shaft 6. This crank shaft 6 has fixed upon it the driving wheels 7 and 75 7^a which gear with wheels 8 and 8^a and mounted upon the cross shaft 9, while upon this cross shaft 9 a driving wheel 10 is fixed to mesh with a pinion wheel 11 carried by the main driving shaft 12, upon which the 80 driving pulley 13 is fixed. Thus as said pulley 13 is rotated the shaft 6 will be rotated and will cause the cranks 5, 5^a to recipro- 85 cate the cylinder 3 as it is guided by the slots 2 in the framework B. Upon the other end of the shaft 12 is fixed a balance wheel 13^a. Formed centrally upon the same shaft 6 is another crank 14, see Fig. 4, which by its connecting rod 15, engages with the sliding block 16 so that said sliding block is 90 also made to recipro- 95 cate vertically by the rotary motions of said crank shaft 6, the positions of the cranks 5 and 5^a being opposite to the position of the crank 14 so that as the cranks 5 and 5^a have the cylinder 3 in its lowest position, the crank 14 will have the sliding block 16 in its highest position and vice versa.

Acting within the cylinder 3 is a piston 17 the stem of which has fixed upon it at its 100 lower end the pressing tool 18 which is arranged to take into one or other of the molds 19^a formed in the rotary die plate 19 as hereinafter described.

Fixed upon the upper end of the sliding block 16 is another pressing tool 20, which as it is reciprocated, is also made to enter one or other of the molds 19^a formed in the 5 die plate 19. Thus as this latter pressing tool enters the mold in the die plate 19 by moving upward the pressing tool 18 will simultaneously enter the same mold by moving downward so that the granulated substances 10 contained by said mold will be pressed evenly between them from beneath as well as from above.

The piston 17 is forced in a downward direction by a spring 17^a mounted within 15 the cylinder 3, in order normally to keep the shoulder 17^x thereon against an internal shoulder formed within the cylinder 3 as shown by Fig. 4, while within this said cylinder 3 and above the piston 7 a liquid 20 (preferably oil) is placed so that as said cylinder 3 and its piston descend to compress the contents of the mold said liquid withstands the pressure within same.

Leading through the end of the cylinder 25 3 is an opening 3^c, within which a double valve 3^f, 3^g is mounted as shown by Fig. 4. These two valves are kept upon their seatings by a spring 3^h acting against the washer 3^e fixed upon the shank of the inner smaller 30 valve 3^f.

Beyond the end of the cylinder 3 a cavity or vessel 21 is mounted so that any oil or liquid escaping from the cylinder 3 through the opening 3^c and past the valves 3^f, 3^g may 35 enter said vessel 21.

Mounted above the valves 3^f, 3^g is a lever 22 (pivoted at 22^x to a sliding bearing 22^y taking within bearings 22^b) the bearings 22^y for which are forced in a downward direction by the recoil of a spring 22^a mounted 40 within the bearings 22^b, one end of said lever 22 having depending from it a rod 22^c while the other end is connected to a ram 23. This ram 23 extends from acting 45 within a cylinder 24 to which the pressure liquid from the cylinder 3 is conducted through a pipe 24^a as shown by Figs. 4 and 6, the same pipe also connecting through the duct 24^b said pressure liquid to a pressure gage 25. The liquid as it passes from the cylinder 3 through the tube 24^b to the cylinder 24 has to pass beyond a valve 26 50 which is opened by a lever 27 (in manner hereinafter described) when the desired pressure in the cylinder 3 is reached and has 55 been released as hereinafter described. The ram 23 working within the cylinder 24 is forced in a downward direction under the pressure of the two springs 24^a, 24^b, which 60 are mounted upon the screwed rods 24^c, 24^d respectively upon which the wheel nuts 24^e, 24^f are mounted, in order that by an elongated pinion 28 being rotated by the hand wheel 28^a said springs may be increased or 65 diminished in pressure to limit or regulate

the maximum pressure that has to be exerted upon the briquets being produced.

When the mold 19^a is brought beneath and above (i. e. between) the pressing tools 18 and 20 the operating cranks commence 70 to move these tools so that they enter said mold. In doing so the cylinder 3 is caused to descend and the upward pressure of one pressing tool and the resistance of the substances within the mold as the cylinder is 75 drawn in a downward direction by its connecting rods 4 and 4^a, causes the liquid within the cylinder 3 to be placed under pressure at which time it is forced along the tube 24^b through the valve 26 to act upon 80 the ram 23 within the cylinder 24 in order to force said ram in a vertical direction against the tension springs 24^a, 24^b. When this pressure has reached a point where it overcomes said springs, it commences to 85 move the ram 23 vertically thereby compressing the spring 22^a within the bearings 22^b, at which time the end of said lever 22 which is coupled to the rod 22^c acts as a 90 fulcrum for said lever 22 by reason of said rod 22^c pressing upon the stem of the valve 3^f. By the ram 23 continuing to rise the bearings 22^b are forced to recede into the bearings 22^b, compressing the spring 22^a until the solid part 22^w of the bearings 22^b 95 comes into contact with the lower end of the fixed bearings 22^b, after which as the ram 23 further rises then the central part 22^v of the lever 22 becomes the fixed fulcrum so that said lever 22 will then commence to 100 force the rod 22^c in a downward direction.

As the rod 22^c is then pressing upon the stem of the smaller valve 3^f its continued descent forces and moves said valve from its seating and permits the liquid within the cylinder 3 to escape into the vessel 21. In this manner the pressing tools and mechanism are relieved of the excessive pressure when the proper limit has been reached as 105 had previously been adjusted for or regulated by the adjustments of the springs 24^a and 24^b. These valves 3^f and 3^g are of the duplex kind illustrated so that by the inner valve being small it will only relieve to a 110 limited extent the extreme pressure described, thereby letting such relief action at this time recoil upon the several parts of mechanism; however, immediately said relief has been effected the rod 22^c moves farther under the recoil of the spring 22^a, which 115 acts upon the lever 22 (at which time the fulcrum of the lever 22 will be at its end which is connected to the ram 23, and its continued motion will cause the stem of the valve 3^f to carry the washer 3^e so that this 120 latter presses upon the stem of the valve 3^g), thus opening the second valve 3^g and thereby immediately letting such of the liquid contents of the cylinder 3 escape into the vessel 21 as circumstances may require. 125 130

The adjustment of the springs 24^a and 24^b may be carried out so that any desired pressure as indicated by the pressure gage 25 may be secured as the requirements of the 5 granulated materials to be briqueted may necessitate.

On the pressing operations being completed and the pressure on the liquid in the cylinder 3 being relieved, the valve 26 will 10 be closed by the recoil of its spring. Thus the liquid within the cylinder 24 will be imprisoned therein and consequently the valves 3^a and 3^b will remain open to permit the liquid that had previously escaped from the 15 cylinder 3 to the vessel 21, to return to the said cylinder 3.

The cylinder 3 then commences to rise and in order to enable the liquid imprisoned in the cylinder 24 to escape therefrom, I mount 20 a lever 27 upon an extension 24^w (which is fixed to the cylinder 24 while this latter is fixed to the cylinder 3 so as always to move with same) in such manner that the end 27^b thereof may take beneath a bar 27^a fixed to 25 the framework B, by which means as the cylinder 3 continues to rise (after the operations stated) the end 27^b of the lever 27 comes into contact with the bar 27^a and is thereby caused to oscillate upon its pivot so 30 that its other end 27^c will engage with the sliding rod 27^d and raise same to lift the valve 26 from its seating thus opening the passage 24^b to the cylinder 3. During the 35 time that the cylinder 3 is thus in its raised position the valve 26 is kept open by the lever 27 to enable the fluid to act as is hereinbefore described.

In order to reduce the speed at which the main crank shaft 6 revolves as the pressure 40 on the briquet increases, the driving belt from the driving pulley 13 is arranged to take over a driving pulley 42 (which pulley 42 is in the form of a box for containing any appropriate kind of differential toothed 45 gearing as for example that described in the specification of my British Patent No. 18761 of 1912) fixed upon the sleeve 46^a of a bevel wheel 46 which wheel and sleeve 46 and 46^a run loosely upon the shaft 47. The shaft 50 50 47 is mounted to run loosely in the bearings C and D which may be supported on the floor of a building or upon the roof of same or in any suitable position. Upon the said shaft 47 is mounted a disk 48 55 (the same being arranged to slide thereon and to rotate therewith by means of a keyway or feather) the periphery of which is covered with leather or the like so that it may form suitable contact with a driving 60 disk 49. This driving disk 49 is fixed upon the end of a shaft 50 carried by bearings or supports 51 so that at its other end a driving pulley 52 may be fixed in order that any main driving belt may transmit motion to 65 said driving pulley 52 and therefore to the

disk 49. Fixed upon the same shaft 50 is a bevel wheel 53 which gears with the bevel wheel 46 hereinbefore referred to. The face of the disk 49 is forced into contact with the periphery of the disk 48 by means of 70 the spring 54. The disk 48 is moved longitudinally over the shaft 47 by the fork lever 43 which is actuated by a piston within the pressure cylinder 44, said piston within the cylinder 44 being connected to the lever 43 75 by means of its rod 43^a. Pressure liquid from the cylinder 3 is conducted to the cylinder 44 by means of the pipe 45, so that the pressure liquid in the cylinder 44 forces the lever 43 to move in the direction indicated by the arrow 60, while the reverse motion of said lever 43 is effected by the recoil of the spring 55. The actions of this apparatus are as follows:—

At the commencement of the pressing operations, the disk 49 is rotated by the main driving belt rotating the pulley 52, and the disk 48 is rotated by said disk 49 at a comparatively slow speed. At the same time the wheel 53 is rotating the wheel 46 so that 90 the speeds of the differential gear within the box 42 are approximately equal; therefore the box 42 which forms the driving pulley transmits motion to the machine at a comparatively quick rate. On the pressure increasing in the cylinder 3 as the briquet becomes more and more compressed, said pressure is transmitted to the piston within the cylinder 44 causing same to move the lever 43 in the direction indicated by the arrow 100 60. Thus the speed of the disk 48 is gradually increased as its position of contact with the disk 49 reaches a position nearer the outer edge of said disk 49. This increased speed of the disk 48 is transmitted to the 105 shaft 47 and therefore the speed of the driving box 42 is gradually reduced by the ratio effected through the differential gearing within said box 42. Thus the pressure of the cylinder 3 is enabled to control the speed 110 at which the crank 6 is actuated.

Although I have described the cylinder 3 as being used directly for transmitting power to the pressing tools, the piston of such cylinder together with its rapid relief 115 devices may be used to act as means for supporting the fulcrum of a lever arranged to carry the pressing tool in which case the crank mechanism would operate said lever, which, on the desired pressure being reached, 120 would have its fulcrum relieved by the controlling pressure cylinder, in the manner hereinbefore fully described.

As means for filling or feeding the granulated substances to the molds 19^a, a hopper 125 50 has propelling blades of any well known formation, mounted to rotate within it and these blades are rotated by gearing wheels 51, 51^a, 51^b, chain wheel 52, chain, and chain wheel 52^a, the latter being fixed upon so as 130

to rotate with the crank shaft 6 as shown by Fig. 3. The hopper 50 has preferably three discharge nozzles 50^a, 50^b and 50^c.

Such being the nature and object of my 5 said invention, what I claim is:—

1. In a briquetting machine a rotary crank, means for rotating said crank, a cylinder reciprocated by said crank, a piston within said cylinder, a pressing tool fixed to said 10 piston, a valve within said cylinder, means for operating said valve by a ram actuated by the pressure liquid in the cylinder, means for controlling the actions of said ram, a receptacle for receiving the liquid escaping 15 from the pressure cylinder and means for controlling the return of said liquid to the pressure cylinder.

2. In a briquetting machine a rotary crank, means for rotating said crank, a cylinder reciprocated by said crank, a piston within 20 said cylinder, a pressing tool fixed to said piston, a valve within said cylinder, means for operating said valve by a ram actuated by the pressure liquid in the cylinder, means 25 for controlling the actions of said ram, a second pressing tool arranged to be operated by a supplementary crank on the main crank shaft, a die plate for receiving the substances to be pressed and means for rotating 30 said die plate between the pressing tools.

3. In a briquetting machine a rotary crank, means for rotating said crank, a cylinder reciprocated by said crank, a piston within 35 said cylinder, a pressing tool fixed to said piston, a valve within said cylinder, means for operating said valve by a ram actuated by the pressure liquid in the cylinder, a valve for controlling the actions of said ram,

a device carried by the cylinder for controlling the movements of said valve and a 40 rotary plate or mold for receiving the substances to be briquetted.

4. In a briquetting machine a rotary crank, a cylinder reciprocated by said crank, a piston within said cylinder, a spring for normally keeping said piston with its shoulder against an internal flange in said cylinder, a valve mounted in the end of the cylinder so that the internal pressure of said cylinder shall normally keep said valve closed, a 45 lever for acting upon said valve, said lever having its central fulcrum mounted upon a spring actuated bearing and means for actuating said lever.

5. In a briquetting machine a rotary crank, a cylinder actuated by said rotary crank, a pressing tool actuated by the piston of said cylinder, releasing valves operated by the pressure of the liquid in said cylinder, means whereby said liquid under pressure is conducted so as to actuate driving mechanism to reduce the speed of said mechanism in accordance with the increasing pressure of the liquid within the cylinder and means for reversing the actions of said actuating 60 mechanism.

6. In a briquetting machine, duplex pressing tools, a crank for operating said pressing tools, a rotary die plate and means for causing same to travel intermittently between said pressing tools, gearing for transmitting motion to said pressing tools and differential gearing in conjunction with friction driving disks for controlling the motion of the driving gear.

CHRISTIAN KORTE.
